CLAIM

The ornamental design for an in-wall speaker system, as shown and described.

DESCRIPTION

FIG. 1 is a top, front and left side perspective view of an in-wall loudspeaker showing my new design;

FIG. 2 is a front elevational view thereof;

FIG. 3 is a side elevational view thereof, the other side being a mirror image of this view;

FIG. 4 is a top plan view thereof;

FIG. 5 is a bottom plan view thereof;

FIG. 6 is a rear elevational view thereof;
FIG. 7 is a top, front and left side perspective view of a second embodiment of the in-wall loudspeaker illustrated in FIG. 1;

FIG. 8 is a top, front and left side perspective view of a third embodiment of the in-wall loudspeaker illustrated in FIG. 1; and
FIG. 9 is a front elevational view of the embodiment disclosed in FIG. 8.

The top, bottom, rear and side views of the second and third embodiments are the same as the first embodiment of the in-wall loudspeaker.
